UNITED STATES PATENT OFFICE.

HARRY H. PUGH, OF TOPEKA, KANSAS.

SILO-DOOR.

1,264,857.

Specification of Letters Patent. Patented Apr. 30, 1918.

Application filed February 28, 1916, Serial No. 80,887. Renewed February 19, 1918. Serial No. 218,172.

To all whom it may concern:

Be it known that I, HARRY H. PUGH, a citizen of the United States, residing at Topeka, in the county of Shawnee and State 5 of Kansas, have invented certain new and useful Improvements in Silo-Doors, of which the following is a specification.

This invention relates to silo doors of the vertically swinging type and has to do in 10 particular with the suspension whereby the door is opened and closed. The main object of my invention is economy; that is to say, it is the object to equip the door with a suspension that is strong, durable, efficient, and 15 simple, and as well convenient in operation, at a minimum cost.

In the drawings accompanying and forming part of this specification and in the description of the drawings I have shown my 20 invention in its preferred form and what I deem to be the best mode of applying the principles thereof; and it is to be understood that, within the scope of the appended claims, I contemplate changes in form, 25 portions, and materials, the transposition of parts, and the substitution of equivalent members, without departing from the spirit of my invention.

Figure 1 is an outside elevation of one 30 complete door equipped with my improved suspension, together with adjacent portions of the door frame, and parts of adjacent doors. Fig. 2 is a sectional plan on a plane indicated approximately by the line 2—2 in 35 Fig. 1. Fig. 3 is a vertical sectional elevation on a plane indicated by the line 3—3 in Fig. 1, with a dotted outline of the door and suspension in the door's open position.

Similar reference characters indicate similar parts throughout the views.

4 is the body of the silo and 5, 5 are the door jambs which project outwardly. These jambs are preferably continuous from the bottom to the top of the silo, and are connected at intervals by cross-pieces 20, so as to form a series of rabbeted door openings 6, 6. The rabbeting is on the inner side, and the door 7 is fitted therein so to be, when closed, substantially flush with the inner side of the wall, in order to offer no obstruction to the proper settling of the silo contents. Secured on the outer side of the door and extending from top to bottom thereof adjacent to the respective jambs, are the two 45 braces or cleats 8, 8. The two straps 9, 9 are secured to the outer face of these braces

or cleats above the vertical middle of the door, to form bearings for the suspension rod 10, which is horizontally disposed in and between said bearings. Immediately outside each of said bearings, the rod turns at a right angle to the rod 10 and extends angularly upward and away from the door, as indicated at 11, 11. These upwardly and outwardly extending portions are then 60 bowed inwardly in general semi-circular form, as indicated at 12, 12 and then extended in directions opposite to each other and parallel with the portion 10, as indicated at 13, 13. The two portions 13, 13 65 are in horizontal alinement with each other and form the axis or pivots on which the suspension turns. Said portions 13, 13 have their bearings in the two jambs respectively. One of the portions 13 has a crank arm 15 70 rigidly secured thereto outside the jamb, and the attachment may be accomplished by an angular end 14 or otherwise; and washers 18, 18 may be provided to prevent wear and properly position the suspension in its bearings. When the door is closed, the crank arm extends upwardly and is fastened by 75 means of a suitable rack, latch or catch 16. To hold the door open, a latch or catch 17 is provided below the pivots for engaging 80 the crank arm.

The door being in closed position, as indicated in the full outlines, it is opened by swinging the crank arm downwardly to its 85 position engaged by the latch or catch 17. 90 To release the crank arm from the catch 16 it is only necessary to press it slightly to the right (viewed in Fig. 1). The downward swing of the crank arm causes the horizontal portion 10 of the suspension to swing inward and upwardly against the inner face of the silo above the door opening, while the bowed portion extends down around the lintel 20 at the top of the opening. This leaves the opening substantially unobstructed. The catch 17 holds the door in its 95 open position. To close the door, the operation is reversed; that is, the crank arm is released from the catch and swung upward and engaged by the catch 16. There is some 100 springiness in the crank arm, and the parts are so adjusted that the crank arm engages the catch 16 under some degree of pressure 105 so as to hold the door tightly closed.

By placing the bearings 9, 9 on the outside face of the door and above the middle, thereby locating the center of gravity below

and inwardly from these bearings, the door, when not otherwise influenced tends to tilt its lower end outwardly and its upper end inwardly; and this tilting serves when opening the door to clear its upper end from the contiguous lintel, and when closing the door the tilting serves to bring the lower end of the door into the side rabbeting to seat itself; so that the opening and closing can be accomplished by the mere manipulation of the crank arm, without by hand or otherwise guiding the door, either out of or into its seat.

Having thus described my invention, what I claim is:

1. In combination with a silo door and door frame having outwardly projecting jambs and inwardly facing rabbeting, said door fitting in said rabbeting; of bearings secured on the front face of said door above the middle thereof, a rod having a horizontal portion mounted in said bearings, said rod being turned at right angles to said horizontal portion outside said bearings and extending thence angularly upwardly and outwardly and thence bowed inwardly and thence extending in opposite directions to form a pair of horizontally alined pivots bearing in said jambs above the lintel of the door frame, one of said pivot portions extending through its jamb, a crank arm secured on said extending end, and catches secured to the frame for holding the crank arm and associated parts in opened and closed positions; said crank arm being adapted through said suspension member to open and close said door by vertical movement of the door.
2. In combination with a silo door and frame; of bearings secured to the outer face of the door above its center of gravity; a rod formed with a horizontal portion mounted in said bearings, portions on oppo-

site sides of said bearings turned upwardly and outwardly therefrom and said upturned portions being bowed inwardly and downwardly and terminating in horizontally alined pivot members bearing in the frame jambs above the lintel; a crank arm secured to one of said pivot members; and means for holding the crank arm in adjusted positions; said door being adapted to be swung inwardly and upwardly by the inward and upward swing of the suspension member on its said pivots to open said door, and said bowed portion extending down under the lintel when the door is in open position.

3. In combination with a silo door and frame; of a rod formed with a horizontal portion having pivotal connection with the door above its center of gravity and extending upwardly and outwardly from said bearing and thence bowed inwardly and terminating in horizontally alined pivot members pivotally mounted in the frame adjacent to the top of the door; a crank arm secured to said rod for operating the same; and means for holding the crank arm in adjusted position.

4. A suspension device for silo doors, comprising the combination of a rod formed with a horizontal portion adapted to be pivotally secured to a silo door above its center of gravity, upwardly and outwardly extending portions continuing from the opposite ends of said horizontal portion, the upper ends of said upwardly and outwardly extending portions being bowed inwardly and downwardly and terminating in horizontally alined pivot members adapted to be pivotally mounted in the door frame above the lintel; together with a suitable lever for operating said rod.

In testimony whereof I have affixed my signature.

HARRY H. PUGH.
